HOUSING FOR INTERIOR LIGHTING

Samuel C. Miller, New York, N. Y.

Application October 17, 1941, Serial No. 415,347

7 Claims. (Cl. 173—328)

This invention relates to insulator housings for electrical devices—more particularly to the provision of an insulator housing for gaseous discharge illuminants, such as are commonly referred to as neon sign tubing.

It is the object of my invention to provide an insulator housing having terminals for neon sign tubes wherein lighting employing gaseous discharge type tubing illuminants may be conveniently used, especially for interior illumination, and provide an insulator housing wherein surface mounting may be effected without the hazard usually attending terminal devices of this character.

More particularly my invention contemplates the provision of an insulator housing for electrical terminals of neon lamps or similar gaseous discharge tubing wherein illuminants of this character may serve the double purpose for arranging illuminating tubes in a series connection or for direct connection to a transformer while mounting the same upon a surface, such as the wall or ceiling without employing cumbersome boxes or panels affixed to the throat of such housings.

Still more particularly, my invention has for its object the provision of an insulator housing and terminal contact device for the purposes indicated, particularly in a gaseous discharge type of illuminant or neon tubing wherein the hazard attending the use of this device is avoided, whether high voltage or low voltage is employed.

Further objects of my invention reside in the provision of an insulator housing and terminal device for a neon sign tubing type of illuminant, which is so formed and proportioned to prevent finger access to live contacts or connections, and which will meet with the approval of safety measures enforced by Underwriters Laboratories.

Still further objects of my invention reside in simple, efficient and novel terminal mounting of the contact elements of the terminal insulating housing of my invention and a coordinately constructed housing for facilitating the mounting of said contacts.

The attainment of the aforementioned objects will be more particularly pointed out hereafter, or will become apparent as this description proceeds.

For this purpose I make reference to the accompanying drawing, forming a part hereof, wherein—

Figure 1 is a perspective view of a double interior housing and terminal device in accordance with my invention;

Figure 2 is a longitudinal section taken on the line 2—2 of Figure 1;

Figure 3 is a transverse section taken on the line 3—3 of Figure 1;

Figure 4 is a plan view of my device;

Figure 5 is a fragmentary bottom view, the parts being broken away to disclose the interior construction;

Figure 6 is a side elevation illustrating my device as a cable transformer terminal housing;

Figure 7 is a magnified fragmentary sectional view of a cable terminal.

Making reference to the drawings, I have illustrated in Figure 1 my combination insulator housing and terminal device 10, the shell whereof may be made of any insulating material, such as porcelain, glass or the like. The housing is formed of a body portion 11, having twin cylindrical sections 12, joined by a partition 13, defining cylindrical orifices 14. The upper end of the cylindrical sections 12 are provided with inwardly directed flanges 15, defining an orifice 16.

The partition 13 has formed centrally thereof the orifice 17, terminating in a shoulder 18. The shoulder 18 is spaced from the lower edge 19 of the sections 12, providing thereby an air gap 20. The shoulder 18 is formed with an orifice 21, through which is disposed an eyelet or grommet 22, formed with a screw threaded orifice 23, into which I dispose the set screw 24, the head of which serves to hold in position the coiled electrode spring contacts 25, which are axially positioned within the orifices 14 of the twin section 12.

With an assembly as provided, there is disposed a cap 26 which has an inwardly directed lip 27, but otherwise interfits with the edge 19 of the housing. The cap 26 is contoured to conform to the twin sections 12 and the laterally directed ears 28 extended from the same. Complementary orifices 29 are provided in the ears 28 and cap 26 through which grommets or eyelets 30 are disposed, and have the turned over portions 31 binding the ears 28 and cap 26 to each other.

The lowermost turned over portion 31 operates with the lugs 32 to provide a base permitting flush contact with some surface such as the wall ceiling bracket of any interior for mounting purposes. The orifice of the grommets 30 serves as the means for fastening elements such as a screw 33 to be disposed to engagement with the wall W and hold the housing in position.

It is to be observed that I have referred to the flange 15 as defining an orifice 16 materially smaller than the orifice 14 of the twin sections

12-12. In my construction the size of the orifice 16 is so disposed in relation to the position of the contacts 25 as to avoid any possible hazard preventing finger access to the contacts 25. The spacial position of the contacts 25 from the cap 26 and the orifice 16 conforms with Underwriters Laboratory safety requirements in that an adequate air gap is provided below the point of suspension of the contacts 25, and an orifice is dimensioned in proportion to its distance from the contact to render finger access to a live connection improbable.

By my construction, wherein the orifices 14 are larger than the orifices 16, a wide tolerance for inaccuracy of bending of the glass tubing 34 is possible. Thus, while it is intended that where the discharge tubing 34 is to be disposed to have its electrode end 35 in contact with the terminal 25 to axially position the same within the orifice 14, should inaccuracy in bending or displacement caused by mounting position the electrode end 35 to a non axial position illustrated in Figure 2, my construction permits of this variation without interfering with the insulator value of the housing. Thus, by my construction full protection against electrical hazards is provided by a housing which takes up materially less space than those under underwriters' requirements previously known to me to be enforced.

While I have described and illustrated in Figure 2 a double interior housing for surface mounting which is peculiarly valuable for neon sign tubes arranged in a series connection, my housing is capable of use for a single section of tubing. For this purpose I have illustrated in Figure 6 the electrode end 36 disposed within an orifice 14 of my terminal housing. In the remaining orifice 14 I may dispose a cable 37 having a contact cap 38 for engagement of the remaining terminal 25. This cable may be connected to the transformer, as will be readily understood by those skilled in the art.

It will thus be observed that I have provided a double interior insulator housing of the terminal device which is capable of utility for a variety of purposes and of such compactness as to effect economy in space while permitting the use of the device for interior illumination and for surface mounting of illuminating devices of the character contemplated.

Having thus described my invention and illustrated its use, what I claim as new and desire to secure by Letters Patent is:

1. An electrode insulator housing for tubular gaseous illuminants comprising in combination, a body portion formed of insulator material defining a chamber open at opposite ends thereof, a partitioning element of insulator material dividing said chamber into twin recesses, extending from adjacent the front end to a point short of the back end of the chamber, leaving a shoulder adjacent one end of said chamber, which shoulder is common to said recesses, said shoulder cooperating with fastening elements forming mounting means for metallic contacts and being disposed from both ends of said chamber to provide a substantial insulating air gap to either side of said shoulder into which the contacts extend resiliently and a cap of insulating material positioned on the back end of said body.

2. An electrode insulator housing for tubular gaseous illuminants including an electrode for connection with a metallic terminal contact carried by said housing comprising in combination, a body formed of insulator material defining a

chamber, a longitudinally exposed partitioning element of insulator material longitudinally dividing said chamber into twin recesses extending from adjacent the front end towards the back end of said chamber, leaving adjacent but spaced from the back end of said body, a shoulder common to said recesses, said partition including an elongated recess therein terminating adjacent said shoulder and disposed in a position accessible to said front end of the body, said shoulder having a portion formed thereon cooperating with a fastening element serving as mounting means for the metallic terminal contact for the electrode of said illuminant.

3. An electrode insulator housing for tubular gaseous illuminants comprising, in combination a body formed of insulator material defining a chamber, a partitioning element of insulator material dividing said chamber into twin recesses, said partitioning element being extended to leave a shoulder adjacent but spaced from one end of said chamber formed with a longitudinally disposed orifice, and providing a mounting element common to said recesses accessible through the orifice of said partitioning element, and metallic contacting elements being disposed substantially axially in said recesses and affixed to said shoulder at a point spaced from the bottom end of said chamber into which said elements move for displacement axially and leaving a substantial air gap from both ends of said chamber and into which the contacting elements extend resiliently.

4. An electrode insulator housing for tubular gaseous illuminants comprising a body formed of insulator material defining a chamber, a partitioning element of insulator material adjacent one end of said chamber dividing said chamber into twin recesses, inwardly directed flanges disposed from said body and partitioning element forming a restricted mouth for said recesses adjacent one end, said partitioning element being extended short of the opposite end of said chamber leaving a shoulder common to both recesses, and providing in cooperation with fastening elements and an aperture on said shoulder, mounting means for metallic contacts common to both recesses, the space between the shoulder and the last mentioned end providing clearance for displacement axially of said contacts and leaving a substantial air gap disposed from both ends of said chamber.

5. An electrode insulator housing for tubular gaseous illuminants comprising a body formed of insulator material defining a chamber, a partitioning element of insulator material adjacent one end of said chamber dividing said chamber into twin recesses, inwardly directed flanges disposed from said body and partitioning element forming a restricted mouth for said recesses adjacent one end, said partitioning element being longitudinally extended short of the opposite end of said chamber, leaving a shoulder common to both recesses, and providing in combination with a fastening element, mounting means for metallic contacts common to both recesses while leaving a substantial air gap disposed from both ends of said chamber, contacting elements comprising resilient branches, the end portions of which branches are anchored on said shoulder, and a cap forming a closure for said body portion, said closure having attaching means connecting the same with ears on said body portion, said closure serving as mounting means for said housing.

6. An electrode insulator housing for tubular gaseous illuminants comprising a body formed of insulator material defining a chamber, a partitioning element of insulator material adjacent one end of said chamber dividing said chamber into twin recesses, inwardly directed flanges disposed from said body and partitioning element forming a restricted mouth for said recesses adjacent one end, said partitioning element being extended short of the opposite end of said chamber leaving a shoulder common to both recesses, and providing mounting means for metallic contacts common to both recesses while leaving a substantial air gap disposed from both ends of said chamber, said partitioning element being recessed longitudinally and terminating into a recess adjacent said shoulder, fastening means engaging the walls of the recess formed in said shoulder, metallic contacts disposed from resilient branches connected by said fastening means to said shoulder at a point spaced from the opposite end of said chamber and forming an air gap, fastening ears disposed exteriorly of said

body and a cap having ears aligned with said first ears, fastening elements connecting said ears of said body and cap forming a closure for said body and a base for mounting the housing upon a surface.

7. An electrode insulator housing for tubular gaseous illuminants comprising a body formed of insulator material defining a chamber open at both ends, partitioning means disposed substantially centrally thereof dividing said chamber into twin recesses, inwardly directed flanges adjacent one end of said recesses, said partitioning means being extended towards the opposite end of said body portion forming a shoulder common to both recesses and spaced from the end to provide a substantial air gap, contacting elements having resiliently displaceable branches mounted upon said shoulder, a closure adjacent said last mentioned end including means engaging said body portion, said closure being formed with portions to support said housing upon a surface.
